C. APPEL.
RAIL CHAIR.
APPLICATION FILED APR. 2, 1919.

1,325,460.

Patented Dec. 16, 1919.

Inventor.

C. Appel.

By *C. Appel*, Attorney.

UNITED STATES PATENT OFFICE.

CARL APPEL, OF SOUTH PASADENA, CALIFORNIA.

RAIL-CHAIR.

1,325,460.

Specification of Letters Patent. Patented Dec. 16, 1919.

Application filed April 2, 1919. Serial No. 286,961.

To all whom it may concern:

Be it known that I, CARL APPEL, a citizen of the United States, residing at South Pasadena, in the county of Los Angeles and State 5 of California, have invented certain new and useful Improvements in Rail-Chairs; and I do hereby declare the following to be a full, clear, and exact description of the invention, such as will enable others skilled in the art 10 to which it appertains to make and use the same.

My invention relates to improvements in rail chairs and more particularly to the fastening means therefor.

15 An important object of this invention is to provide a rail chair including a base plate having openings adapted for the reception of spikes and novel means for securely retaining the spikes in engagement with the 20 base of a rail.

A further object of the invention is to provide a rail brace which may be stamped from metal and cheaply produced in large quantities.

25 Other objects and advantages of this invention will be apparent during the course of the following description.

In the accompanying drawing, forming a part of this specification and in which like 30 numerals are employed to designate like parts throughout the same:

Figure 1 is a perspective of a rail chair constructed in accordance with my invention applied to a rail,

35 Fig. 2 is a perspective of the same detached,

Fig. 3 is a perspective of a tongue adapted for use in connection with the chair shown in Fig. 2,

40 Fig. 4 is a perspective of a slightly modified form of the invention, and

Fig. 5 is a perspective of a tongue adapted for connection and use with the chair shown in Fig. 4.

45 In the drawing, wherein for the purpose of illustration is shown the preferred embodiment of my invention, the numeral 5 designates a railroad tie and the numeral 6 designates a rail.

50 In the form of my invention illustrated in Figs. 1 to 3 inclusive, the numeral 8 generally designates a base plate having a slot 9 extending longitudinally of the same and formed integral with a rail brace 10. As

55 illustrated in Fig. 1, the upper end of the

rail brace 10 engages with the adjacent portions of the web and ball of the rail. The lower portion of the brace 10 is bent outwardly to conform to the configuration of the base of the rail and is provided with a 60 slot 11 registering with the slot in the base plate 8. A locking tongue 12 is adapted to be arranged in the slot 9 and have one end extend beyond the base plate 8 as indicated in Fig. 1. One end portion of the base plate 65 8 is provided with spike receiving openings 13 adapted for the reception of spikes 14. L-shaped caps 15 are carried by one end of the locking tongue 12 for engaging the top of the spikes 14 and retaining the same in 70 rigid contact with the base of the rail. The opposite end of the tongue 12 is provided with an opening 16 adapted for the reception of a spike 17. Upon engaging the base of the rail, the head of the spike 17 is disposed within the slot 11 of the brace 10.

In applying this form of the invention, the chair is first arranged beneath the rail and the brace 10 engaged with the web and ball of the rail. Subsequently to the driving of the spikes into the openings 13, the locking tongue 12 is driven into the slot 9 and the caps 15 engaged with the spikes 14 for retaining the same in position. A spike is now driven through the opening 16 for 85 retaining the locking tongue in position and also for engaging the rail as indicated.

In the form of my invention illustrated in Figs. 4 and 5, A base plate 18 is provided with a slot 19 opening out through one end 90 of the same. A rail brace 20 is formed integral with one end of the base plate and has its lower portion curved as indicated at 21 for conforming to the configuration of the rail. The opposite end of the base plate is 95 provided with openings 22 adapted for receiving spikes. A locking tongue 23 is adapted to be arranged in the slot 19 and is provided with L-shaped tongues 24 adapted for engaging the heads of the spikes and retaining the same in contact with the base of the rail.

In the form of my invention illustrated in Figs. 4 and 5, each alternate rail brace is arranged on opposite sides of the rail whereby 100 the rail is rigidly supported.

While I have shown and described the preferred embodiment of my invention, it is understood that such minor changes in arrangement and construction of parts may 110

be made as will remain within the spirit of the invention and the scope of the appended claims.

Having thus described my invention, what I claim is:—

1. A rail chair comprising a base provided with a slot opening out through one end thereof, a rail brace carried by the other end of the base, a tongue arranged in said slot, and spike engaging caps carried by the tongue.
2. A rail chair comprising a base provided with a slot opening out through one end thereof, said base being provided at said end with spike receiving openings, a rail brace carried by the other end of the base, a tongue arranged in said slot, and spike engaging caps carried by the tongue.
3. A rail chair comprising a base provided with a slot opening out through one end thereof, said base being provided at said end with spike receiving openings, a rail brace carried by the other end of the base and having its lower portion curved to conform to the configuration of the rail, a tongue arranged in said slot, and spike engaging caps carried by said tongue.
4. A rail chair comprising a base pro-

vided with a slot opening out through one end thereof, said base being provided at said end with spike receiving openings, a rail brace carried by the other end of the base and provided with a spike receiving opening registering with said slot, a tongue arranged in said slot, and spike engaging caps carried by the tongue adjacent said first named spike receiving openings, said tongue being provided with a spike receiving opening registering with said second named opening.

5. A rail chair comprising a base provided with a slot, said base being provided at one end with spike receiving openings, a rail brace carried by the other end of the base, a tongue snugly arranged in said slot and having one end terminating flush with one end of the said base, and L-shaped caps carried by one end portion of said tongue for engaging the spikes extended through said spike receiving openings.

In testimony whereof I affix my signature in presence of two witnesses.

CARL APPEL.
